UNITED STATES PATENT OFFICE

LESLIE R. N. CARVALHO, OF TOLEDO, OHIO, ASSIGNOR TO THE CLOSURE SERVICE COMPANY, OF TOLEDO, OHIO, A CORPORATION OF OHIO

CLOSURE

Application filed October 3, 1927. Serial No. 223,640.

The present invention relates to improvements in jar closures, and particularly to that type embodying a screw threaded attaching flange.

In applying closures of the above character to jars or like receptacles, the closure is given a twisting movement which, just prior to final seating of the closure, often causes mutilation of the paper or cardboard liner which is interposed between the button or top portion of the closure and the sealing or finish end of the jar. Such mutilation of the liner is frequently caused by imperfect or rough surface formations on the sealing end of the jar which become embedded in the liner and tear or otherwise mutilate such liner as it creeps during application of the closure to the jar.

An object of the present invention is to provide novel means to overcome the above objection without materially adding to the cost of production of the closures or complicating the application of the closures to containers. To this end, the invention, in its preferred embodiment, consists in interposing a relatively thin disk, of metal or other suitable material, between the button or top portion of the closure and the paper liner, said disk being of less diameter than that of the closure and adapted to provide a smooth hard bearing surface upon which the button of the closure rotates during the latter part of its application to a container. Thus, no movement whatsoever is transmitted to the paper liners while they contact with the sealing end of the receptacle, either during application or removal of the closure, and consequently the liner is not distorted or mutilated.

Other objects will be apparent hereinafter.

In the accompanying drawings:

Fig. 1 is a fragmentary sectional view showing the application of the present invention, and

Fig. 2 is a side elevation illustrating the relation between the closure and the several disks which are placed therein.

In the drawings, the jar or receptacle 10 is illustrated as formed with a reduced neck 11 having external screw threads 12 which are engaged with threads 13 formed on the

depending annular flange 14 of a sheet metal cap including a flat button or top disk 15. While other forms of liners may well be used, I have shown for the purpose of the present application, a relatively heavy cardboard disk 16 which is snugly fitted into the closure and faced with a thin wax coated paper disk 17 or the like, the latter adapted to rest upon the sealing end or finish 18 of the jar.

According to the present invention, there is interposed between the cardboard disk 16 and the button 15 of the closure, a relatively light disk 19 of metal or other suitable material, which provides a bearing surface for said button and spaces the latter out of contact with the usual liners. This metal disk 19 is perfectly flat and of less area than that of the inner face of the closure button so that it has free movement in the space between the button 15 and the cardboard lining disk 16. Thus, during the latter portion of the application of the closure to a jar or the like, there will be effected a relative movement between the contacting faces of the button 15 and metal liner 19, rather than between the usual lining disks and the sealing end or finish 18 of the jar 10. Accordingly, the liner is forced downwardly, without rotation, into snug sealing contact with the upper end of the jar and there is no distortion of the liner.

In addition to providing means minimizing or entirely eliminating distortion or mutilation of the liner and consequent imperfect sealing of the jar, the placing of the disk 19 as described greatly facilitates loosening and removal of the closure.

Modifications may be resorted to within the spirit and scope of the appended claim.

What I claim is:

The combination with a container having an externally screw threaded neck, of a closure cap therefor comprising a flat circular top and a screw threaded depending flange to engage the threads on said neck, a circular flat metal bearing plate within the cap parallel with and in contact with said top, said plate being of considerably less area than the inner face of the top portion, a liner within the cap parallel with and in contact with the lower face of said bearing plate, said liner

having a wax facing on the side opposite the bearing plate, said liner being of an area to snugly engage its periphery with the flange of the cap and thereby hold said cap, plate and liner together prior to application of the cap to the container and preventing contact of said liner with the upper surface of the container during the application of the cap to the container, except while the liner is being compressed between the upper surface of the container and the marginal portion of the bearing plate and said top during the final rotative movement of the cap as the latter is screwed home on the container.

Signed at Toledo, in the county of Lucas and State of Ohio, this 29th day of September, 1927.

LESLIE R. N. CARVALHO.
